US00D837236S

(12) **United States Design Patent** (10) **Patent No.:** **US D837,236 S**
(45) **Date of Patent:** **** Jan. 1, 2019**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventor: **Eunji Choi**, Seoul (KR)

(73) Assignee: **Samsung Electronics Co., Ltd.**,
Suwon-si (KR)

(**) Term: **15 Years**

(21) Appl. No.: **29/574,726**

(22) Filed: **Aug. 18, 2016**

(30) **Foreign Application Priority Data**

Feb. 19, 2016 (KR) 30-2016-0007713

(51) **LOC (11) Cl.** **14-04**

CLAIM

I claim the ornamental design for a display screen or portion thereof with graphical user interface, as shown and described.

DESCRIPTION

The sole FIGURE is a front view of a display screen or portion thereof with graphical user interface showing the new design.

The broken lines in the FIGURE depict environmental

subject matter and form no part of the claimed design.

The outermost broken line in the FIGURE shows a display screen or portion thereof and forms no part of the claimed design.

1 Claim, 1 Drawing Sheet
